THERMOSTATIC CONTROL UNIT

Siegfried E. Manecke, Indiana, Pa., assignor to
Robertshaw Controls Company, Richmond, Va.

Filed Aug. 21, 1974, Ser. No. 499,133

Term of patent 14 years

Int. Cl. D10—04

U.S. Cl. D10—50

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a left front perspective view of a thermostatic control unit showing my new design;
FIG. 2 is a right rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;

FIG. 9 is a front elevational view of a second embodiment of my new design of FIG. 1 wherein the terminal lugs are again arranged differently;
FIG. 10 is a front elevational view of a third embodiment of my new design of FIG. 1 wherein the terminal lugs are again arranged differently;
FIG. 11 is a front elevational view of a fourth embodiment of my new design of FIG. 1 wherein the terminal lugs are again arranged differently;

FIG. 12 is a front elevational view of a fifth embodiment of my new design of FIG. 1 wherein the terminal lugs are again arranged differently;

FIG. 13 is a front elevational view of a sixth embodiment of my new design of FIG. 1 wherein the terminal lugs are again arranged differently;

FIG. 12 is a front elevational view of a fifth embodiment of my new design of FIG. 1 wherein the terminal lugs are again arranged differently.

All other views for the second through fifth embodiments are substantially identical with those of FIGS. 1-8 with the exception of the lug arrangements shown.

I claim:

The ornamental design for a thermostatic control unit, as shown and described.
